CLAIM

We claim the ornamental design for a hood for a floor care appliance, as shown and described.

DESCRIPTION

FIG. 1 is a perspective view of a hood for a floor care appliance showing our new design;

FIG. 2 is a top view thereof;

FIG. 3 is a front side view thereof;

FIG. 4 is a right side view thereof; and,

FIG. 5 is a left side view thereof.

The details shown in broken lines form no part of the claimed design.
